UNITED STATES PATENT OFFICE

153,126

DESIGN FOR A KITCHEN RANGE

Montgomery Ferar, Detroit, Mich., assignor to
Sears, Roebuck and Co., Chicago, Ill., a corpo-
ration of New York

Application December 10, 1947, Serial No. 143,090

Term of patent 7 years

(Cl. D81—4)

To all whom it may concern:

Be it known that I, Montgomery Ferar, a citizen of the United States of America, and a resident of Detroit, county of Wayne, and State of Michigan, have invented a new, original, and ornamental Design for a Kitchen Range, of which the following is a specification, reference being had to the accompanying drawing, forming a part thereof.

Fig. 1 is a perspective view of a kitchen range, showing my new design; and

Fig. 2 is a side elevational view of a kitchen range, showing the new design, the other side being similar and symmetrically opposite.

The dominant features of the design reside in the portions shown in full lines.

I claim:

The ornamental design for a kitchen range, substantially as shown and described.

MONTGOMERY FERAR.
